(57) **CLAIM**

The ornamental design for a stethoscope holder, as shown and described.

DESCRIPTION

FIG. 1 is a perspective view of a stethoscope holder, showing my new design;

FIG. 2 is a bottom view thereof;

FIG. 3 is a top side view thereof;

FIG. 4 is a right side view thereof;

FIG. 5 is a left side thereof;

FIG. 6 is a front view thereof; and,

FIG. 7 is a rear view thereof.

The broken lines shown in the views are directed to environment and are for illustrative purposes only; the broken lines form no part of the claimed design.
